POLISHING MACHINE

Jerome D. Rosenberg, 3 Shadow Lawn Drive,
Livingston, N.J.

Filed Feb. 21, 1964, Ser. No. 78,725

Term of patent 14 years

(Cl. D9—2)

FIGURE 1 is a top plan view of the polishing machine shown in FIGURE 5 with the handle omitted, embodying my new design;

FIGURE 2 is a cross-sectional view taken along the line II-II of FIGURE 1;

FIGURE 3 is a side elevational view;

FIGURE 4 is a front elevational view; and

FIGURE 5 is a side elevational view showing of the design.

The dominant features of my design reside in the portions shown in full lines.

I claim:

The ornamental design of a polishing machine, as shown and described.
